UNITED STATES PATENT OFFICE

162,276

SPIRITUAL CROSS PULPIT

Franklin C. Zemmer, Kansas City, Mo.

Application June 15, 1950, Serial No. 10,524

Term of patent 3½ years

(Cl. D29—23)

To all whom it may concern:

Be it known that I, Franklin C. Zemmer, a citizen of the United States, residing at Kansas City, in the county of Jackson and State of Missouri, have invented a new, original, and ornamental Design for a Spiritual Cross Pulpit, of which the following is a specification, reference being had to the accompanying drawing, forming a part hereof.

Fig. 2 is a side elevational view thereof;

Fig. 3 is a front view thereof; and

Fig. 4 is a plan view thereof.

I claim:

The ornamental design for a spiritual cross pulpit, as shown.

FRANKLIN C. ZEMMER.
